FIG. 2.

UNITED STATES PATENT OFFICE.

JOHN STARRETT AND NEWTON J. WIER, OF LOWELL, MASSACHUSETTS.

GAS-STOVE.

Specification of Letters Patent No. 14,888, dated May 13, 1856.

To all whom it may concern:

Be it known that we, JOHN STARRETT and N. J. WIER, of Lowell, in the county of Middlesex and Commonwealth of Massachusetts, have invented certain new and useful Improvements in Gas-Stoves; and we do hereby declare that the following is a full, clear, and exact description thereof, reference being had to the accompanying drawings, and 10 to the letters of reference marked thereon.

Figure 1, is a plan or top view. Fig. 2, is a vertical section through the center. Fig. 3, is a plan of the distributer, and Fig. 4, is a cross, vertical section of the same.

15 Other figures will be referred to hereafter. Similar letters of reference, in each of the several figures, indicate like parts.

A, Figs. 1 and 2, represents the outer case of the stove, and it may be of a cylindrical 20 form as represented, or any other convenient form.

B, is a temporary top piece, of a cylindrical form, and made so as to fit upon the top of the outer case A.

25 C, is a chamber, into which the gas is introduced—from an orifice E, in the gas pipe F, in order to allow atmospheric air to mix freely with it, previous to its being burned.

30 D, is a distributer plate, supported in the upper part of the chamber C, by the three brackets K, K, K. It is composed of three round pieces of metallic plate. The middle one nearly fills the chamber C, leaving only 35 a narrow space between its outer edge and the sides of the chamber. This plate also has a hole in its center, through which the mixed air and gas is intended to pass.

Above and below this hole, at a little distance from it, are fastened two smaller plates, in order that the gas shall not pass too freely through it, and in an unmixed state, as is would do, if merely suffered to rise, unmolested, from the orifice of the gas 45 pipe.

The direction, the current of gas, from the orifice E, is supposed to take, is represented by the arrows, and as the whole inside of the chamber is open to the free access of at- 50 mospheric air, the gas, in passing from the orifice E, up against the distributer, and then branching out every way, until it passes around the various edges of the distributer, must, in its passage, become very freely

55 combined with the air.

Covering the top of the chamber C, is a

fine wire netting (G), or a finely perforated plate; and the mixed gas and air passing through this, is to be ignited on the top, when a pale blue flame will immediately 60 spread itself, very evenly, over the whole upper surface of the wire gauze, consuming the gas so very effectually, that if it is allowed to burn openly in an apartment, but a very slight odor, and that of a perfectly in- 65 offensive kind, can be perceived. This arrangement also so thoroughly mixes the gas with the air, that the combustion produces not the slightest soot on any article held in the flame; thus the cleanest tin or other 70 utensil may be placed directly in the flame and remain any length of time, without becoming soiled. This therefore is an excellent device for housekeepers to heat their sad or flat irons, as well as to do their gen- 75 eral cooking by.

Another improvement we have made is in the registers, which are intended to be used in combination with the wire gauze, and are intended to regulate the "surface of combustion" so as to suit it to utensils of various sizes and shapes. Figs. 5 and 6 are a plan and section of one of these registers. It consists of a circular plate H, of the same size as the top of the chamber C, having a 85 circular hole in the middle of it. This plate is attached to one end of a cylindrical ring I, which is just large enough to fit around the top of the cylinder C, and thus confine the plate H, in its place on top of the wire 90 gauze. Now when this is on, the surface of combustion is confined to the size and shape of the hole in the plate H. Figs. 7, and 8, represent a similar register in construction, with the exception of the shape of the hole 95 in the plate H, which is intended to conform to the shape of a flat or sad iron, and is to be used when such irons are to be heated.

We do not claim the chamber C with its wire covering for the purpose of mixing air 100 with gas, previous to burning; nor their combination with the outer case A, as these devices are already known.

The arrangement and construction of our distributer, renders the combination of gas 105 and air so much more perfect than has hitherto been done, that their combination produces but very little, if any odor, and gets rid entirely of all smoke and soot; so that there is no need, (as there is in previous 110 stoves of this kind) of pipes for conveying to the chimney or "out of doors" offensive

gases or smoke, but on the contrary an open fire may be kept in an apartment with perfect impunity. The plate D, is intended to serve another important purpose and that is 5 in concentrating and saving the heat. Were it not for this, a large amount of heat from the surface of combustion would strike down and be dispersed. As it is, the plate reflects the heat that strikes upon it and thus 10 concentrates it all upon the utensil which is being heated over the surface of combustion.

Having thus described our improvements, what we claim as new, and desire to secure by Letters Patent, is—

- 15 1. The distributer plate D, constructed and arranged substantially as described.
2. The combination of the distributer

plate D, the chamber C, with its net work covering—and the exterior cases A, and B, substantially as herein set forth.

3. The combination of the plates or registers H, H, with the net work covering of the chamber C, for the purpose of varying the surface of combustion to suit the various utensils to be heated, substantially as herein 25 set forth.

In witness whereof we have hereunto set our signatures this 21st day of April A. D. 1856.

JOHN STARRETT.
NEWTON J. WIER.

In presence of us:

NATHANIEL WRIGHT,
O. E. CUSHING.
